UNITED STATES PATENT OFFICE

CHARLES McCURLEY, OF HALFWAY, MICHIGAN, ASSIGNOR TO HUDSON MOTOR CAR COMPANY, OF DETROIT, MICHIGAN, A CORPORATION OF MICHIGAN

SHEET-METAL-WORKING TOOL

Application filed January 14, 1928. Serial No. 246,687.

This invention relates to a tool for curling the free edges of a two-ply metal strip and more particularly, although not exclusively, to a tool for use in assembling sheet metal 5 automobile bodies for crimping the free edges of a molding strip interposed between and extending beyond the flanges of adjoining panels.

In the construction of certain types of 10 closed automobile bodies including sheet metal exterior panels, the adjacent or proximate edges of contiguous panels are formed with inturned flanges which are secured together with the interposed flanges of a molding strip having an enlarged head at the exterior of the body to form a bead which covers and conceals the joint. In accordance 15 with the present invention, the free edges of the molding strip flanges project inwardly 20 beyond the free edges of the panel flanges and are bent or curled thereover to form a rigid interlocking connection, the operation of so bending the flanges serving also to pull 25 the joint together whereby the panels are rigidly drawn into their proper relative positions and the head or bead of the molding strip brought into close engagement with the exterior faces of the panels.

The object of this invention is to provide 30 a simple and inexpensive tool for curling or crimping the free edges of the molding strip.

By the use of this tool, the formation of the panel joints is effected by operations performed wholly at the interior of the body so 35 that danger of accidental injury to the exposed exterior surfaces of the panels is avoided, and pre-finishing of said surfaces permitted.

Other objects of this invention will appear 40 from the following description, reference being had to the accompanying drawings forming a part of this specification, wherein like reference characters designate corresponding parts in the several views and wherein:

Figs. 1 and 2 are side elevations, at right angles to one another, of a curling tool constructed in accordance with the invention.

Fig. 3 is a detail sectional view showing 50 the manner in which the molding strip is

interposed between inturned edges of adjacent panels prior to the curling operation.

Fig. 4 is a detail plan view showing the movement of the curling roll in performing the operation of crimping the free edges of 55 the molding strip, and

Fig. 5 is a detail view, partly in section, showing the ends of the molding strip bent over at the completion of the curling operation. 60

As illustrated in the drawings, the members 1 and 2 of the device are pivotally joined together at 20 after the manner of a pair of tongs, so that when closed they are in substantially overlapping position. The members 1 and 2 include arm portions 3 and 4, and handle portions 5 and 6, respectively. The arm 3 is provided adjacent its free end with a roll 7 while the arm 4 has fixed at its extremity a stud or hook member 8 extending at right angles to the arm. In the preferred embodiment of my invention, the arm 3 is slightly curved near its extremity at 9, and the roll 7 is mounted adjacent the end of the curved portion of the arm upon a laterally 65 extending axis. The roll is offset in this manner in order to increase the length of its working stroke, causing the roll to move across the entire face of the work and beyond the longitudinal plane of the superimposed arms. 70

Any suitable mounting means for the roll may be used such, for example, as the pin or bolt 10 on which the roll 7 is retained by means of the nut 11 and washer 12. The roll 7 has a working or contacting surface composed 75 of a pair of substantially tangential arcuate surfaces or grooves 7^a and 7^b, separated by means of a tapered rib or wedge 7^c.

The arm 4, which carries the stud or hook 8, is sufficiently longer than the arm 3 which carries the roll 7 to permit the hook 8 to extend laterally from the arm 4 in front of the roll 7 and provide the desired clearance between the hook and the path of the roll. 90

As will be seen by reference to Fig. 3, both the inturned flanges of the panels A and B and the free ends G and H of the molding strip flanges are provided in advance with rivet holes, the holes 14 in the inturned flanges C and D, being of somewhat greater diameter 95 100

ter than the holes 15 in the molding strip flanges. This difference in the size of the rivet holes is provided in order that the molding strip may be drawn up slightly at the time the free ends are bent over, thus forming a tighter joint.

In the operation of my device, the hook 8 of the arm 4 is first inserted through the rivet holes 14 and 15. Due to the greater size of the rivet holes 14, the stud 8 will have a slight play therein as described above, enabling the operator to pull up the molding strip, bringing the head F into tight engagement with the panel walls. The tool being thus initially positioned by means of the stud 8, the roll 7 will be in position at one side of the free ends of the molding strip, the tapered rib 7^c being directly in line with the line of division between the free ends G and H of the molding strip flanges. As the handles of the device are closed together, the arm 3 carrying the wiping roll 7 will be drawn across the ends G and H of the molding strip flanges, and due to the arcuate surfaces of the working face of the roll, these ends will be bent outwardly over the ends of the flanges C and D on the panels A and B, as illustrated in Fig. 5.

While I have described herein in detail one embodiment of my invention, it will be understood that many modifications thereof are possible without departing from the spirit of my invention which is to be limited only by the following claim.

35 I claim:

A tool comprising a pair of arms crossed and pivotally joined together, a wiping roll carried by one of said arms, a stud fixed to the other of said arms and extending in a direction parallel with the axis of said wiping roll, and handles for both of said arms.

In testimony whereof I affix my signature.
CHARLES McCURLEY.
